United States Patent Office.

CHARLES B. FRANCIS, OF NEWARK, NEW JERSEY.

Letters Patent No. 60,872, dated January 1, 1867.

IMPROVED WINDOW-BLIND FASTENER.

The Schedule referred to in these Letters Patent and making part of the same.

TO ALL WHOM IT MAY CONCERN:

Be it known that I, CHARLES B. FRANCIS, of Newark, Essex county, and State of New Jersey, have invented a new and useful Device for Holding the Slats of Window Blinds; and I do hereby declare that the following is a full, clear, and exact description thereof.

This invention consists in the employment of a slotted bar or lever, that has a turn at right angles, and around which a metallic strap passes, and secured to a window blind in such a manner that the slats of the blind may be held in any desired position. Great difficulty and inconvenience have been experienced after the bearings of the slats of the blinds become a little worn in the stiles or sides of the blinds—they fall down and close, so they cannot be kept in any position except either up or down. By my invention I am able to overcome this difficulty by means of a metallic strap passing around the arm of a slotted lever, which may be tightened by a screw, thus causing friction, so that the slats of the blind may be held at any desired angle or position, which is a matter of great convenience.

To enable others skilled in the art to make and use my invention, I will proceed to describe its construction and operation.

Figure 1 is a side elevation showing my improved device attached to a window blind.

Figure 2 is a transverse vertical sectional elevation from the line X X.

Letters of like name and kind refer to like parts in each of its figures.

A represents the frame of a window blind of common construction. B are the slats, also made in the common way. C is the connecting-bar that connects the slats, and by which they are rolled up and down. D is a metallic strap which I usually make of brass or other sheet metal, and is secured to one of the slats by screws, *a a*. E is a slotted bar or lever that turns at right angles, and a portion of it is round and around, which the metallic strap D passes, and held by the screw, *e*, sufficient to hold the slat of the blind at any desired angle by the friction. As the slat is rolled either up or down, the lever E is guided and moves in the slot upon the screw, O. By this device the slats may be held at any desired angle.

Having thus described my invention, what I claim as new, and desire to secure by Letters Patent of the United States, is—

The metallic strap D, and slotted bar or lever E, for the purpose of holding the slats of window blinds at any desired angle, substantially and for the purposes herein described.

The above specification of my invention signed by me this 10th day of July, 1866.

CHARLES B. FRANCIS.
